UNITED STATES PATENT OFFICE

LEO W. KENNEDY, OF DETROIT, MICHIGAN

CORNER DOOR ASSEMBLY

Application filed December 2, 1929. Serial No. 411,168.

This invention relates generally to show cases and refers more particularly to corner assemblies therefor.

One of the essential objects of the invention is to provide a show case in which the space within the case at a corner thereof is normally closed by a door but is readily accessible.

Another object is to provide a show case of the type described in which a door at the corner thereof may be easily and quickly removed from or returned to closed position.

Another object is to provide an assembly in which a handle serves as a means by which the door may be manipulated and also constitutes a brace and reinforcement between wing portions of the door.

A further object is to simplify, render more efficient, and improve generally the assembly as a whole.

Many other objects, advantages, and novel details of construction of this invention will be made more apparent as this description proceeds, especially when considered in connection with the accompanying drawings, wherein:

Figure 1 is a fragmentary perspective view of a show case with a corner assembly embodying my invention;

Figure 2 is an enlarged elevation of a portion of the corner assembly and showing the removable door in both lowered and raised positions;

Figure 3 is a horizontal sectional view taken on the line 3—3 of Figure 1;

Figure 4 is a vertical sectional view taken on the line 4—4 of Figure 1;

Figure 5 is a sectional view taken on the line 5—5 of Figure 1.

Referring now to the drawings, 1 is a counter or table having portions A and B disposed at substantially right angles to each other, and C is a show case of the closed type having portions D and E respectively disposed at substantially right angles to each other and resting on the portions A and B respectively of the counter. As shown, the show case C includes a plurality of pillars 2 on the counter, a plurality of top rails 3 on the pillars, a top 4 of L configuration on

the rails, doors 5 closing the spaces between the pillars 2 of the respective sections D and E, and a door 8 closing the space between adjacent doors 5 at the corner F of the show case. Preferably each pillar 2 comprises a metal part 11 and a wooden part 12. As shown, the metal part 11 of the pillar 2 just to the left of the corner F is substantially flat and is disposed at substantially right angles to the edge 13 of the counter, while the metal part 11 of the pillar just to the right of the corner F is preferably flat and is disposed at substantially right angles to the edge 14 of the counter. The wood part 12 of the left hand pillar is square in cross section and is secured to the right side of the metal part 11 in advance of the rear edge 15 thereof, while the wood part 12 of the right hand pillar is also square shape in cross section and is secured to the left side of the metal part 11 in advance of the rear edge 16 thereof. The rails 3 are preferably inverted L shape in cross section, the horizontal portions 18 thereof being secured to the upper ends of the pillars 2 and supporting the top 4, and the depending portions 19 overlapping and secured to the rear edges 15 and 16 respectively of the metal parts 11 of the pillars 2 located at the left and right sides respectively of the corner F. Brackets 20 are secured between the wood and metal parts 11 and 12 respectively of the left and right hand pillars at the lower ends thereof and have lateral flanges 21 extending over but spaced from the inner faces of the wood parts 12. The doors 5 may be any suitable construction and may be mounted in any suitable manner. Preferably these doors normally engage the pillars 2 and may, if desired, be pivotally mounted thereon. The door 8 is preferably light sheet metal stamping of L cross section corresponding to the angle formed by the rails 3 and is provided intermediate of its ends with a handle 30 by which it may be manipulated. Preferably the upper edges of the door 8 are received in the spaces provided between the flat inner faces of the wood parts 12 and the depending flanges 19 of the rails, while the lower edges of the door 8 are received in the spaces 100

provided between the lower faces of the wood parts 12 and the lateral flanges 21 of the brackets.

Thus with the present construction the space within the show case at a corner thereof, heretofore inaccessible, may now be reached easily and quickly by merely lifting the door 8 from the pillars. Moreover, the handle 30 by which the door may be lifted constitutes a brace between the wing sections 31 and 32 respectively of the door and strengthens and reinforces the same.

While it is believed that from the foregoing description the nature and advantages of my invention will be readily apparent, I desire to have it understood that I do not limit myself to what is herein shown and described, and that such changes may be resorted to when desired as fall within the scope of what is claimed.

What I claim as my invention is:

1. In a show case, a corner assembly including spaced pillars, rails disposed at substantially right angles to each other having portions secured upon the pillars and having other portions overlapping certain faces of the pillars, and a movable door having portions received between the overlapping portions and the faces aforesaid of the pillars.
2. In a show case, a corner assembly including spaced pillars, brackets carried by said pillars at the lower ends thereof and having lateral portions overlapping certain faces of the pillars, top supporting rails disposed at substantially right angles to each other having portions secured upon the upper ends of the pillars and having other portions overlapping certain faces of the pillars, and a movable door having portions received between the lateral portions aforesaid and said pillars, and having other portions detachably received between the overlapping portions of the rails aforesaid and said pillars.
3. In a show case, a corner assembly including spaced pillars, rails disposed at substantially right angles to each other having portions secured upon said pillars, bracket means carried by said pillars adjacent the lower ends thereof, and a removable door having portions detachably received between said brackets and the adjacent portions of said pillars.

In testimony whereof I affix my signature.
LEO W. KENNEDY.
